UNITED STATES PATENT OFFICE

WALTER E. HOLLAND, OF PHILADELPHIA, PENNSYLVANIA, ASSIGNOR TO PHILADELPHIA STORAGE BATTERY COMPANY, OF PHILADELPHIA, PENNSYLVANIA, A CORPORATION OF PENNSYLVANIA

BINDING POST

Application filed July 3, 1929. Serial No. 375,849.

This invention relates to improvements in binding posts and similar devices for the retention of electrical conductors, and the principal object of the invention is to provide a simple and inexpensive spring-type binding post consisting of a minimum number of parts and having as characteristic features thereof ease of assembly and installation.

Another object of the invention is to provide a binding post so constructed that the operation of attaching an electrical conductor thereto is an extremely simple and relatively easy one, and in which the conductor is securely held until such time as it may be desirable to break the connection.

In the attached drawings:

Figure 1 is a view in perspective of a binding post made in accordance with my invention;

Fig. 2 is an enlarged vertical section through the binding post and the base to which the post is secured, and

Figs. 3 and 4 are fragmentary perspective views illustrating modifications within the scope of the invention.

With reference to the drawings, 1 is a column of conducting material having a reduced base portion 2. 3 is a collar which receives the said base portion 2 and is adapted for mounting in a supporting structure or member which in the present instance is constituted by a plate 4 of insulating material. In the present instance, the collar 3 has a reduced lower extension fitting within an aperture in the plate 4 and a flange 5 which rests upon the top of the plate and affords a substantial bearing between these parts. The reduced part 2 of the column 1 projects beyond the lower end of the collar, and after receiving washers 6 and 7 and between these a soldering lug 8 is riveted over to secure the column in place, the support 4 being securely clamped between the flange 5 and the washer 6.

The column 1 has at the top a transversely enlarged part or head 9 and below the head a transverse passage 10 which in size is somewhat larger than the largest diameter of conductor which the binding post is adapted to hold. Slidably mounted upon the column

1 is a sleeve 11 preferably of insulating material, such as Bakelite, which is of sufficient width at the bottom to easily embrace the collar 3 and which is turned inwardly at the top to more or less closely embrace the upper portion of the column 1, the sleeve 11 thus being free to move longitudinally of the column but being confined by the head 9. Surrounding the column 1 in the interior of the sleeve 11 is a spring 12 which rests at the bottom upon the top of the collar 3 and bears at the top against the turned-in portion of the sleeve 11. This spring normally holds the sleeve 11 against the under side of the head 9, but permits the sleeve to be moved downwardly for insertion of a conductor 13 through the passage 10, as illustrated. Thereafter, release of the sleeve 11 permits the spring to force the sleeve up against the conductor to thereby clamp and hold the latter in position. It will be noted that there is a shearing action between the upper end edges of the passage 10 and the upper edges of the opening of the sleeve 11 through which the column 1 extends whereby a firm grip is established upon the conductor preventing accidental displacement of the latter and at the same time forcing the conductor into good electrical contact with the conducting column 1. It will be noted also that the spring is completely housed within the sleeve 11 and is not exposed.

In Fig. 3, the passage provided in the column 1 for reception of the conductor 13 extends from the side of the column at a point below the head 9 upwardly on a slant to the top end surface of the column, this passage in Fig. 3 being designated by the reference numeral 10a. This provides that one end of the conductor-receiving passage shall be accessible at the top of the column, which somewhat facilitates insertion of the wire.

In Fig. 4, the top of the column 1 is shown as provided with a cap of insulating material. There may be other modifications without departure from the invention.

I claim:

1. A binding post comprising a column of conducting material having a lower reduced portion and at its upper end a passage adapt-

ed for reception of a wire conductor, at least one end of said passage terminating in the side of the column, means for mounting the column in a supporting structure including a
5 collar closing embracing the reduced lower portion of the column and adapted at its lower end to engage the said supporting structure, the lower end of said column projecting below the collar and the supporting structure
10 and being adapted to be expanded to thereby secure the column in the structure, a spring surrounding the upper end of the column and seated upon the top of said collar, and a sleeve also surrounding the column and having a
15 part at the top closely embracing the column and forming an abutment for the upper end of the spring whereby the spring is adapted to resiliently retain the sleeve against a wire conductor inserted in said passage to clamp
20 the conductor in the column.

2. A binding post comprising a column of conducting material having a lower reduced portion and at its upper end a passage adapted for reception of a wire conductor, at least
25 one end of said passage terminating in the side of the column, means for mounting the column in a supporting structure including a collar closely embracing the reduced lower portion of the column and adapted at its lower end to engage the said supporting structure, the lower end of said column projecting below the collar and the supporting structure, means at the lower end of said column for securing the latter in the structure, a spring surrounding the upper end of the column and seated upon the top of said collar, and a sleeve also surrounding the column and having a part at the top closely embracing the column and forming an abutment for the upper end
35 of the spring whereby the spring is adapted to resiliently retain the sleeve against a wire conductor inserted in said passage to clamp
40 the conductor in the column.

WALTER E. HOLLAND.
